UNITED STATES PATENT OFFICE

2,455,756

MECHANISM FOR SUPPLYING STEAM AND HEATED AIR TO SPOTTING MACHINES

William C. Glover, Jr., Kansas City, Mo., assignor to Bill Glover Incorporated, a corporation of Missouri

Application February 18, 1946, Serial No. 648,268

3 Claims. (Cl. 68—6)

1

This invention relates to improvements in a mechanism for supplying steam and heated air to a dry cleaner's spotting machine and refers more particularly to a device which combines a steam receptacle and air heater with connections for supplying steam and heated air optionally to the nozzle of a spotting board.

Heretofore it has been common practice to supply live steam to the nozzle of a spotting board from a convenient source of steam and provide moisture in varying quantities to the steam according to the particular spotting operation to be performed. In cleaning spots from garments or fabrics which have been dry cleaned, the character of the spots to be removed to a great extent will determine the amount of moisture desired in the steam used in removing the spot.

It is desirable to furnish steam to the nozzle with the desired moisture content and optionally provide a supply of heated air through the nozzle for drying the fabric after the spotting operation has been completed or alternately with steam during spotting.

An object, therefore, of the invention is to provide a spotting board equipped with a nozzle through which either air or steam may be supplied, with a novel control device for the air and steam valves whereby one valve is closed when the other is opened.

Another object is to provide an air heater arranged in novel heat exchange relation with the steam supply so air and steam may be optionally furnished to the nozzle of the spotting board.

A further object is to provide an air heat exchanger by which the heat of the steam used in the spotting machine may be efficiently transmitted to the air used optionally with the steam during the spotting operation.

Other and further objects will appear from the following description.

In the accompanying drawings which form a part of the specification and are to be read in conjunction therewith, and in which like reference numerals indicate like parts in the various views,

Fig. 1 is a side elevational view of a spotting machine embodying the invention with parts broken away, and

Fig. 2 is a detail of the upper portion of the steam receptacle showing the valve control mechanism.

In the drawings, wherein for the purpose of illustration is shown a preferred embodiment of the invention, the numeral 10 designates a pedestal having a base portion 10a. On top of

2

the pedestal is mounted a shallow pan 11 covered by a perforated plate or foraminous screen 12. At one end of the pan is a tray 13 and at the low end of the pan is a drain opening 14 below which is hung a bucket 15 upon a hanger 16. Beneath the pan and attached to the pedestal is a narrow loop of pipe 17 forming the frame for a canvas garment catcher which is laced to the pipe. Within the pedestal and bolted thereto is a steam receptacle 18, equipped with a steam inlet pipe 19 and a steam outlet pipe 20. Integrally formed on the side of the steam receptacle or affixed thereto in heat exchange relation as by welding is a hollow casing or housing 21. This housing has a lower air inlet 22 and an upper outlet pipe 23. Interposed in the outlet pipe is a valve 24. Screwed into the top of the receptacle 18 is a steam valve 25 whose construction forms the subject of copending application Serial No. 582,111, filed March 10, 1945. This valve serves a dual purpose of supplying dry steam or relatively wet steam to the nozzle of the spotting board. The upper portion of the valve designated in the drawings by the numeral 25a has a discharge connection 26 communicating through a nipple in the pedestal with the hose 27 to which nozzle 28 is attached. Adjacent the nozzle is a handle 29. Portion 25a of the valve is also connected by pipe 30 to air valve 24.

The control for the steam and air valves 24 and 25 comprises a pedal-operated vertical lever 31 pivoted on shaft 32 in the base 10a of the pedestal. A horizontal pedal 33, mounted on the pivot 32, tilts in two directions. The upper end of lever 31 is connected by link 34 to a rocker arm 35 pivoted at 36 within the pedestal. To the opposite end of the rocker arm is connected a vertical rod 37 whose upper extremity is threaded and screwed into the throat of yoke 38.

The bifurcated ends of the yoke 38 embrace and are attached to an arm 39 pivoted at 40 upon bracket 41. At the opposite end of the arm 39 is supported a weight 42. A flattened portion of the underside of arm 39 contacts the top of the valve rod which opens the steam valve against the forces of a compression spring and weight 42 when pivoted arm 39 is rocked. The details of this steam valve, as previously noted, are disclosed in and form the subject of my copending application. Affixed to valve 24 is a bracket 43 to which is pivoted an actuating arm 44. The free end of this arm has an eye or ring through which rod 37 passes. Below the end of the arm and adjustably affixed to rod 37 by a set screw is a collar 45. The upper surface of arm 44 ad-

jacent bracket 43 contacts the lower end of a spring pin which actuates valve 24. The interior of heater 21 is provided with extended surface to increase the effectiveness of the heat exchange between the steam passing through receptacle 18 and air passing through heater 21. This extended surface may take the form of fins, metallic wool such as copper or bronze shavings, preferably noncorrosive to the media passing through the heater.

In operation, the worker stands at the side of the machine where the pedal is located, places the fabric to be cleaned on the perforated surface 12 of the pan 11. He removes the nozzle 28 from its slot in the side of the pan and if steam is to be applied to the fabric, pedal 33 is pressed to the left of its pivot. This moves lever 31 and link 34 to the left, depressing rod 37 through the action of rocker arm 35. As rod 37 is pulled downwardly, horizontal arm 37 through yoke connection 38 is tilted and the steam valve is opened allowing steam to enter discharge line 26. Through this pipe the steam is supplied through hose 27 to the nozzle. If it is desired to inject heated air into the fabric during the spotting operation, pedal 33 is pressed to the right of its pivot 32 shifting lever 31 and link 34 to the right which rocks pivoted arm 35 to raise rod 31. Collar 45 then contacts the end of the actuating arm 44 to raise the actuating pin of the air valve 24, permitting heated air supplied through pipe 23 to the valve to be discharged through pipes 30, 26 and hose 27 to the nozzle.

Thus it will be seen that optionally with the operator steam of the desired moisture content or heated air may be furnished to the spotting operation by the simple tilting of pedal 33 to one side or the other.

From the foregoing it will be seen that this invention is one well adapted to attain all of the ends and objects hereinabove set forth, together with other advantages which are obvious and which are inherent to the structure.

It will be understood that certain features and subcombinations are of utility and may be employed without reference to other features and subcombinations. This is contemplated by and is within the scope of the claims.

As many possible embodiments may be made of the invention without departing from the scope thereof, it is to be understood that all matter herein set forth or shown in the drawings is to be interpreted as illustrative and not in a limiting sense.

Having thus described my invention, I claim:

1. In a spotting board, a spotting nozzle, a receptacle having a steam inlet and a steam outlet, a discharge line connecting the receptacle to the nozzle, a valve in the discharge line for controlling the flow of steam therethrough to the nozzle, an

air supply line connected to said discharge line, a valve in the air line for controlling the flow of air through the air line to the discharge line and hence to the nozzle, the air supply line including an elongated tube supported by the receptacle on the outside thereof with the wall of the tube in engagement with the wall of the receptacle to facilitate the transfer of heat therebetween, an actuating device common to said valves and movable in either direction from a neutral position, and linkage from the device to the valves adapted to open only one valve when the device is moved in one direction from neutral and to open only the other valve when the device is moved in the other direction from neutral.

2. In a spotting board, a spotting nozzle, a receptacle having a steam inlet and a steam outlet, a discharge line connecting the receptacle to the nozzle, a valve in the discharge line for controlling the flow of steam therethrough to the nozzle, an air supply line connected to said discharge line, a valve in the air line for controlling the flow of air through the air line to the discharge line and hence to the nozzle, the air supply line including an elongated tube supported by the receptacle on the outside thereof with the wall of the tube in engagement with the wall of the receptacle, and heat conducting elements within said tube to facilitate the transfer of heat from the walls thereof to the air passing through the tube.

3. In a spotting board, a spotting nozzle, a receptacle having a steam inlet and a steam outlet, a discharge line connecting the receptacle to the nozzle, a valve in the discharge line for controlling the flow of steam therethrough to the nozzle, an air supply line connected to said discharge line, a valve in the air line for controlling the flow of air through the air line to the discharge line and hence to the nozzle, the air supply line including an elongated tube supported by the receptacle on the outside thereof with the wall of the tube in engagement with the wall of the receptacle, and a metallic wool within said tube to facilitate the transfer of heat from the walls thereof to the air passing through the tube.

WILLIAM C. GLOVER, JR.
